CLAIM

The ornamental design for a process cartridge for image forming apparatus, as shown and described.

DESCRIPTION

1. Process cartridge for image forming apparatus
1.1 is a front elevation view of a process cartridge for image forming apparatus showing our new design;
1.2 is a rear elevation view thereof;
1.3 is a top plan view thereof;
1.4 is a bottom plan view thereof;
1.5 is a left side elevation view thereof;
1.6 is a right side elevation view thereof;
1.7 is a bottom, rear, and left side perspective view thereof;
and
1.8 is a top, front, and right side perspective view thereof.

1 Claim, 8 Drawing Sheets
